JOHN H. LAUKEL, OF DETROIT, MICHIGAN

METHOD OF MAKING MULTIPLE CORE BOXES

Application filed April 2, 1930. Serial No. 441,125.

The present invention pertains to a novel method of producing a multiple core box by electro deposition.

As well known in the art, a core box is ordinarily accompanied by a set of core driers into which the cores are transferred from the core box after being molded therein and after removing one of the halves of the core box. In other words, the core drier is laid over the half of the core which is exposed by removal of half of the core box, and then both the box and the drier are inverted, after which the half of the core box formerly holding the core is lifted so that the core remains seated in the drier. It will be readily understood that if a core box for simultaneously producing a number of cores were provided, it would be necessary that the drier to receive the cores should have the core seats or pockets located exactly in register with the corresponding seats or pockets of the core box. Otherwise, in case of misalignment, at least some of the cores would not be properly received in the drier and would be mutilated in the attempted transfer from core box to core drier.

From a practical and economical standpoint it is exceedingly difficult and expensive by present methods to form one or more multiple core boxes that will register accurately with the core driers. Considerable skill and accurate work are necessary in making driers that will accurately fit the core boxes, and the expense involved is almost always prohibitive.

The formation of the working surface of a multiple core box by electro deposition lends itself to the production of a core box which is accurate with respect to the drier. According to the invention, it is necessary to have only a single cavity core box made by prior methods or by electro deposition. A number of split cores are made from this box and laid out on a flat surface for the purpose of molding the pattern of a multiple core drier over them. A cathode for the deposition of the multiple core box is constructed from cores set in the core drier as a guide so that the core seats in the deposited box register perfectly with those of the drier. Cores

made in the deposited core box may therefore be transferred readily to the core drier without risk of mutilation.

The invention is fully disclosed by way of example in the following description and in the accompanying drawings in which

Figure 1 is a sectional view illustrating the manner of form and core drier pattern over a plurality of half cores;

Figure 2 is a sectional view illustrating the manner of locating cathode bodies with respect to the core drier;

Figure 3 is a sectional view illustrating the manner of fixing the cathode bodies on a cathode base;

Figure 4 is a section showing the manner of similarly assembling the cathode for the other half of the core box;

Figure 5 is a sectional view of a completed cathode;

Figure 6 is a detail section of a cathode with a deposit thereon.

Reference to these views will now be made by use of like characters which are employed to designate corresponding parts throughout.

As already indicated, the core box is built with reference to the core drier, and in Figure 1 is illustrated the first step in the formation of the drier. A plurality of half cores 1 made from a perfect single cavity core box are laid upon a base 2 in the relation in which it is desired to have the core receiving pockets in the core driers and core box. These half cores have dowel holes 1' to receive dowel pins for holding the half cores in matched relation when necessary, as will presently appear. A pattern 3 is molded over the sections 1 in any suitable manner, as by pouring plaster of Paris over the sections and trimming it after setting to the form desired for the pattern. The wall 4 of the pattern may conveniently be made of strips of wood.

From the pattern is cast the desired number of core driers, one of which is indicated by the numeral 5 in Figure 2. The corners 6 of the core pockets are relieved, for a purpose well known in the art, by similarly relieving the corners of the original pattern. It may be stated in this connection that if a number of driers is desired, a metal pattern

is made from the original pattern, and the driers are cast from the metal pattern.

The core drier 5 is now turned face up, and the half cores 1 are seated therein. In order to maintain the half cores firmly in proper position, the relieved parts of the drier are filled with a plastic substance 7. The half sections 1 are associated with matched counterpart sections 8 which are now laid upon the sections 1 in matched registration therewith and fixed thereto by any suitable means such as dowel pins in the holes 1'. Over the counter parts 8 is formed a cast 9 of any suitable material, such as plaster of Paris, adapted to hold the counterparts 8 in the same relative position as the half cores 1 on which they are mounted. Holes 10 are drilled from the top of the cast 9 through the matched core sections, preferably at the core prints, and then through the core drier as indicated by the numeral 11. These holes are tapped where passing through the cores as indicated by the numeral 12.

The purpose of the cast 9 is to enable removal of the counterparts 8 without destroying the relation which has been determined by the core drier. The cast is then removed and placed upon a slab 13 which is to constitute the base or carrier of a cathode. The drilled holes 10 are extended through the slab as at 14, for example, by sinking a drill into the holes and working it through the slab, or by spotting on the top of the slab, removing the cast and cores, and drilling from the spots. At the base of the slab a countersink 15 is formed at each hole 14, and a headed screw 16 is inserted from the countersink in each hole and threaded into the superposed core section 8. The cast 9 is now ready for removal from the core sections, which is enabled by oiling the sections prior to the formation of the slab thereon. In this manner there is formed a body similar to that shown in Figure 5 and on which the half cores are located in the same relation as the core pockets in the drier.

In like manner the drier 5 containing the sections 1 is inverted upon a slab 17 which is to constitute the base of the cathode for the deposition of the other half of the core box. Holes 18 are drilled in the slab 17 in alinement with the holes 10 in the drier and are countersunk at 19. Headed screws 20 are passed through the holes 18 and threaded into the tapped holes 12 of the core sections whereby these sections are secured on the slab 17 in the same relation as on the slab 13.

The core sections thus mounted on the slabs are to constitute cathodes for the electro deposition of the working faces of the two halves of the core box. The cathode may be prepared for the bath and for plating in any manner well known in the art. The slab and the core sections thereon may, for example, consist of plaster which is impregnated to

resist attack by the bath and rendered conductive where deposition is desired. As an alternative, the core sections may originally be formed of a low melting metal which requires no metalization for plating and which is readily removed from the deposit by fusing. In either case, the countersinks 15 are plugged with an insulating material 21 to avoid plating on the heads of the screws. The dowel holes 1' are plugged with conducting material. It is also preferred to apply a metal face plate 22 upon the slab and around the margins of the core sections as described in the pending application of Arthur K. Laukel, Serial No. 101,069 filed April, 1926. 80

Figure 6 illustrates a portion of one of the cathodes in the process of deposition. A metal shell 23 is deposited over the core sections, uniting with the face plate 22 and thus forming one of the molding faces of the core box. When a sufficient thickness of metal has been deposited, the shell is backed or reinforced in any suitable manner such as that shown, for example, in the above mentioned application. The two halves of the core box thus formed are then equipped with locating means such that the impressions in each section will register perfectly with those in the other section. This may be done, for example, by placing whole cores in one of the sections, 95 covering the exposed parts of the cores with the other section, and then drilling through both core box parts in this position, whereupon the holes thus formed constitute locating means. Locating pins may be fixed in the holes of one of the core box parts to register with the holes in the other part. 100

Inasmuch as the core cavities in the core box are located in perfect registration with the core seats in the drier, it becomes possible 105 to transfer the cores from the box to the drier without difficulty, and the above mentioned difficulties in the making of the multiple core box by ordinary casting and machining methods are overcome. 110

Although a specific embodiment of the invention has been illustrated and described, it will be understood that various alterations in the details of construction may be made without departing from the scope of the invention as indicated by the appended claims. 115

What I claim is:

1. A method of making a multiple core box consisting in fitting a plurality of split cores in a multiple core drier, locating the counterparts of said split cores in matched registration upon the first named split cores, forming a cast over said counterparts, laying said cast with the counterparts therein upon a slab, securing said counterparts upon said slab in the position maintained by said cast, with the parting faces engaging the slab, removing said cast, and preparing said counterparts and slab for immersion in a plating bath for electro deposition on said counterparts. 120 125 130

2. A method of making a multiple core box consisting in fitting a plurality of split cores in a multiple core drier, locating the counterparts of said split cores in matched registration upon the bottoms of the first named split cores, forming a cast over said counterparts, laying said cast with the counterparts therein upon a slab, securing said counterparts upon said slab in the position maintained by said cast with the parting faces engaging said slab, removing said cast and preparing said counterparts and slab for immersion in a plating bath for electro deposition on said counterparts, laying the core drier with the first named split cores therein upon another slab, and similarly securing said split cores upon said slab, removing the drier from said split cores, and preparing the slab and split cores for immersion in a plating bath and for electro deposition upon said split cores.

3. A method of preparing a cathode for the electro deposition of the working surface of a multiple core box consisting in laying out a plurality of split cores, molding a pattern of a core drier over said split cores, casting a core drier from said pattern, fitting said split cores in said drier, locating the counterparts of said split cores in matched registration upon said split cores, forming a cast over said counterparts, laying said cast with the counterparts therein upon a slab, securing said counterparts upon said slab in the position maintained by said cast, with the parting faces engaging said slab, removing said cast, and preparing said counterparts and slab for immersion in a plating bath for electro deposition on said counterparts.

4. A method of preparing a cathode for the electro deposition of the working surface of a multiple core box consisting of laying out a plurality of split cores, molding a pattern of a core drier over said split cores, casting a core drier from said pattern, fitting said split cores in said drier, locating the counterparts of said split cores in matched registration upon said split cores, forming a cast over said counterparts, laying said cast with the counterparts therein upon a slab, securing said counterparts upon said slab in the position maintained by said cast, with the parting faces engaging said slab, removing said cast, and preparing said counterparts and slab for immersion in a plating bath for electro deposition on said counterparts, laying the core drier with the first named split cores therein upon another slab, and similarly securing said split cores upon said slab, removing the drier from said split cores, and preparing the slab and split cores for immersion in a plating bath and for electro deposition upon said split cores.

In testimony whereof I affix my signature.
JOHN H. LAUKEL.
